UNITED STATES PATENT OFFICE

CHARLES F. PRESCOTT, OF BROOKLYN, NEW YORK, ASSIGNEE OF ONE-HALF TO
WILLIAM A. SELTS, OF BROOKLYN, NEW YORK.

LOCOMOTIVE DRIVING-BOX.

1,219,866.

Specification of Letters Patent. Patented Mar. 20, 1917.

Application filed September 20, 1916. Serial No. 1,1154.

To all whom it may concern:

Be it known that I, CHARLES F. PRESCOTT, a citizen of the United States, and a resident of the city of New York, borough of Brooklyn, in the county of Kings and State of New York, have invented a new and Improved Locomotive Driving-Box, of which the following is a full, clear, and exact description.

10 This invention relates to railway journal boxes and has particular reference to journal boxes or bearings for the driving axles of locomotives.

15 Among the objects of the invention is to provide a journal box made of a plurality of relatively movable parts, certain of said parts being parallel to each other and movable toward each other automatically or otherwise to take up for wear at the front 20 and back portions of the axle.

25 Another object of the invention is to provide a journal box or bearing for a rotating axle having separable and interchangeable brasses for the front and rear portions of the axle to take up for the wear incident to the thrust and the pull of the engine piston.

30 A further object of the invention is to provide a journal box of the character set forth adapted to be inspected or renewed and parts substituted or interchanged without removing the wheels or disturbing the box itself.

35 A still further object is to provide a locomotive journal bearing whose front and rear bearing surfaces are centrally disposed vertically, whereby uniformity of wear is assured.

40 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof, reference is had to the accompanying drawings, in which like reference characters designate the same parts in the several views, and in which

45 Figure 1 is an end elevation of a preferred embodiment of the invention;

50 Fig. 2 is a vertical transverse section of the same;

Fig. 3 is a vertical longitudinal section on the line 3-3 of Fig. 1;

Fig. 4 is a perspective view of the crown 55 piece; and

Fig. 5 is a similar view of one of the front and back pieces or cheek plates.

Referring now more particularly to the drawings I show a journal box structure 60 comprising three main parts, namely, a crown piece 10 and front and rear cheek plates 11 and 12. The cheek plates are shown as being of an approximately rectangular form and substantially flat in general configuration. They are adapted to operate in vertical planes parallel to each other directly in front and at the rear of the axle 13. The effective centers of these cheek plates vertically considered lie in a plane 70 coinciding with the axis of the axle.

The crown piece is longitudinally recessed at 14 along its under surface to receive and retain the main load supporting brass 15. This brass has endwise sliding fit in the recess 14 and has direct contact with the upper portions of the axle. Any suitable means may be provided to retain the brass in the recess 14 except when it is intended to be removed or interchanged. For this purpose, 80 I indicate a set screw 16 acting downwardly through the crown piece into contact with the top of the brass. This crown piece, as heretofore, is adapted to receive the spring saddle (not shown). The crown piece is 85 provided along its front and rear faces with any suitable number or design of lugs 17, shown herein as of cylindrical form and projecting forwardly and rearwardly in opposite direction from each other on opposite 90 sides of the crown piece. The faces 18 of the crown piece from which the lugs 17 project are substantially flat and disposed in parallel vertical planes. Those portions 19 of the crown piece between the recess 14 and the lower portions of the plane faces 18 are plane and lie in the same horizontal plane at right angles to the vertical faces just mentioned.

95 The cheek plates 11 and 12 are or may be 100 substantially alike and a specific description of one and illustration thereof in Fig. 5, may be understood as being applicable to both. Fig. 5 shows the inner face of the cheek plate, the same being provided with 105 a longitudinal recess 20 of any desired form in transverse section, the same being adapted to receive a lateral brass 21. From what

has been stated above, it will be noted that I provide accommodation for two of these lateral brasses which are designed to take the direct bearing thrust or pull on the front 5 and rear faces of the axle incident to the pull and thrust of the engine piston, and thereby I overcome effectively a very common source of trouble and expense in the maintenance of locomotive journal boxes. 10 The upper end of each cheek plate is provided with a hole 22 complementary to the form of the lug 17 adapted to be received therein with a sliding fit. Just below the hole 22 is formed an inwardly projecting shoulder 23, the upper face of which lies in 15 a horizontal plane and takes directly under the adjacent portion or face 19 of the crown piece against which it bears. It will be noted that each cheek plate, so far as the lug 20 17 and coöperating faces 19 and 23 are concerned, is freely slideable inwardly toward the axle, but is held from downward movement by the lug and from upward movement and rotation around the lug by means 25 of the coöperating faces and shoulders 19 and 23.

Each lateral brass 21 is provided with a concave active bearing face in direct coöperation with the axle. The other faces are 20 so formed or related to one another as to provide a sliding fit in the recess 20 of the adjacent supporting cheek plate. As shown, however, plainly in Fig. 2 there is a clearance provided between each cheek plate 25 and the crown piece providing for freedom of movement inwardly toward the axle to compensate for the wear that naturally takes place in the lateral brass carried thereby. Any suitable means may be provided 40 to adjust the cheek plates inwardly toward each other or toward the center of the axle and when so much of the lateral brasses is worn away as to cause the cheek plates to abut against the crown piece, I provide for 45 the insertion of one or more shims 24 between the lateral brasses and the bottoms of the recess 20 so that practically all of the lateral brasses may be used up before they are scrapped. The lateral brasses 21 may 50 easily be withdrawn endwise for interchange or replacement, but are adapted to be held normally in operative position by any suitable means, such as clips 30 locked in place at the ends of the cheek plates by means of 55 set screws 31 or their equivalent.

The cheek plates are provided on their inner faces adjacent their lower edges with recesses or grooves 25 to receive the ribs 26 of a lubricant cellar 27 adapted to slide longitudinally of the axle into the grooves 25 whereby the cellar is supported. The cellar 60 is held from endwise displacement by any suitable form of locking bolt 28 acting through registering lugs or ears 29. The 65 clearance above referred to providing for

the inward movement of the cheek plates obtains also between the sides of the cellar and the cheek plates.

As above premised, the action of the cheek plates toward each other to compensate for the wear of the lateral brasses may be provided for manually or automatically, but the construction as illustrated adapts itself well for automatic adjustment by means of a wedge 32 tapered upwardly toward its upper end and forced upwardly at all times by means of a spring 33 located adjacent the rear portion of the box. A companion wedge 34 having less taper than the main wedge 32 and with its smaller end projected 75 downwardly lies between the main wedge and the cheek plate 12. By virtue of this construction of automatic adjusting means, the cheek plates and lateral brasses carried thereby are always maintained in proper bearing contact with the sides of the axle and resist the thrust and pull of the engine piston without shock or vibration. The automatic adjusting means also insures that there will be no excessive binding action due 80 to vertical vibration of the journal box.

The construction of the journal box shown herein, in which there are relatively movable parts, makes it feasible and practical for certain of the parts to be periodically 95 adjusted as for example, by inserting spacers or liners between the cheek plates and the parts next within them. These liners may be withdrawn from time to time to permit the setting up or adjusting of the cheek 100 plates as may be desired. Since the adjustment or interchange of the journal box or its parts may be effected without removing the wheels from the engine, I provide in this construction a 105 means whereby any lateral motion or slack between the wheel hubs and the boxes may be taken up by simply removing the box and pouring Babbitt or other soft metal liners on the faces of the box which bear 110 against the wheel hub.

In the driving box construction as heretofore ordinarily used, the bearing surface extends down only to the horizontal plane coinciding with the center of the journal. In the modern high powered locomotive the piston pulls and thrusts are so enormous compared to the weight supported on the main supporting brass that the box frequently rises from the journal owing to 120 the fact that the surfaces to resist the thrusts and pulls are at an angle to the line of pull and thrust considerably more or less than a right angle. In this construction, however, it will be noted that the lateral brasses 125 extend well below the horizontal plane of the axis of the journal whereby it is impossible for the bearing surfaces to rise or ride up over the journal because of the enormous thrust or pull. It will be noted also 130

that there is a decided advantage resulting from the increase of bearing surface over ordinary journal boxes. In other words, the wear is distributed over so much increased area that the cutting or excessive wear upon any particular part of the bearing will be reduced to a minimum.

The construction and relative disposition of the bearing parts of my improved journal box provide that the journal will be substantially locked in place with respect to the lubricant cellar carried by the lower edges of the cheek plates. In other words, in the event of derailment of the locomotive, it is impossible in this construction for the journal to drop down away from the crown piece and destroy the lubricant cellar, a matter of considerable importance in practice.

I claim:

1. In a locomotive journal box, the combination of a rigid frame, a crown piece, a pair of front and rear cheek plates, connecting means between the front and rear faces of the crown piece and the upper edges of the cheek plates serving to hold the cheek plates at a constant elevation and prevent tilting thereof with respect to the axis of the journal, but permitting the cheek plates to slide toward each other, the inner faces of said crown piece and cheek plates hav-

ing recesses extending longitudinally of the journal, a series of removable and interchangeable bearing brasses slidably fitted in said recesses, and automatic means acting between the frame and the cheek plates to cause the cheek plates to move toward each other to take up for wear upon the brasses carried thereby.

2. In a locomotive journal box, the combination of a crown piece, front and rear cheek plates movable toward each other and suspended from the crown piece, bearing brasses carried by the cheek plates, and means holding the cheek plates and their brasses with their effective bearing centers in the same horizontal plane as the axis of the journal therefrom.

3. In a locomotive journal box, a crown piece having a longitudinal recess in its under side to receive a brass and lugs projecting from its opposite sides, two cheek pieces each having an opening adjacent its upper end to receive a lug of the crown piece, a longitudinal shoulder below the opening and extending under and engaging the lower face of the crown piece, and a longitudinal groove below the shoulder to receive a brass, and means for forcing the cheek pieces toward each other.

CHARLES F. PRESCOTT.
